JOURNAL LUBRICATOR

James J. Hennessy, Montclair, N. J.

Application October 8, 1947, Serial No. 778,651

5 Claims. (Cl. 308—83)

1

The invention relates to means for recovering excessive lubricating oil supplied to journals, and particularly railway locomotive driving journals from which lubricant would otherwise escape endwise of the journal and be thrown centrifugally from the journal outside the journal box and be lost. The invention is directed to a journal wiper device at the outer end of the lubricator generally of the kind described in Patents Nos. 2,191,468 and 2,327,040 to the present inventor.

One object of the present invention is to provide efficient means of recapturing oil escaping to the outer ends of the bearings of railway vehicle lubricated journals.

Another object is to provide an oil wiper for a railway vehicle journal which readily adjusts itself to the contour of the journal and after such adjustment resists further wear.

Another object is to provide an oil wiper for a railway vehicle journal which may be replaced easily when worn or damaged.

These and other objects are attained by the structure illustrated in the accompanying drawings, in which

Figure 1 is a longitudinal vertical section through an axle box showing the axle journal and a portion of the hub of the wheel mounted thereon, a portion of the journal and lubricant cellar being broken away and the cellar structure, cellar supporting plate, axle box and journal bearing being sectioned to better illustrate the construction.

Figure 2 is an end elevation and a vertical transverse section of the box and associated structure taken approximately on the line 2—2 of Figure 1, and

Figure 3 is a detail top view and horizontal section taken approximately on line 3—3 of Figure 1.

The invention is shown applied to a locomotive driving box having the usual side walls 1 for engagement with the underframe pedestal (not shown) and receiving the crown bearing brass 2 having its outer end undercut as at 3 and rotatably mounting a journal 4. A mechanical lubricator is applied to the box and includes a tank like body or cellar having a bottom wall 5, end walls 6, 7 and side walls 8, 9. The upper edges of these walls extend into downwardly facing recesses 10 in the driving box to avoid the loss of oil. A reservoir 10a projects inwardly from the cellar proper. A pump structure indicated generally at P (actuated by the play of the journal transversely of the box) and a distributor structure indicated generally at D feed lubricant from

the cellar and its reservoir 10a to the lower face of journal 4, by which it is carried around to the bearing 2. All of the above-described structure is well known in the art and in itself does not constitute the present invention.

A journal wiper at the outer end of the lubricator engages the underside of the journal and overlies cellar end wall 6 and extends outwardly and inwardly therefrom. The wiper comprises a pair of quadrant shaped members 11, 12 with their inner ends hooked to each other as indicated at 13. Each member 11, 12 has a depending lug 14 pinned to a depending support 15, the lower end of which is slidably received in a boss 16 on cellar bottom wall 5. A spring 17 is seated on bottom wall 5 and thrusts support 15 and the associated member upwardly.

Each member 11, 12 has a plurality of spaced diagonal upstanding ribs 18 sloping downwardly and inwardly of the journal and adapted to initially engage the journal and to wear quickly to the contour of the journal. Pads 19 of larger area and of less height than ribs 18 are positioned between the ribs and are adapted to engage the journal after the ribs have worn to the journal contour and fully engage the journal. Each pad 19 has a disc 20 of wear resisting material embedded in it to engage the journal face and reduce further wear of the members. The discs are made of hardwood, plastic, fiber or other wear resisting material. Between ribs 18 and pads 19 are inwardly and downwardly sloping depressions 21 to carry excess lubricant away from the end of the bearing and return it to the lubricant cellar. Circumferential ribs 22 extend transversely to ribs 18 near the outer edge of members 11, 12 and prevent flow of oil outwardly of the journal which movement would be most likely to occur along the ribs on the rising side of the journal. Transverse ribs 22 are substantially the same height as diagonal ribs 18 and are adapted to wear quickly to the journal contour.

The oil supplied to the journal by the pump is carried upwardly by the rising side of the rotating journal between the journal and the bearing to lubricate the same. Surplus oil between the journal and the bearing tends to travel longitudinally of the latter to the ends of the bearing. The oil reaching the undercut end 3 of the bearing brass 2 tends to adhere to the rotating journal. Most of this oil is wiped from the journal by the inner portions of ribs 18 but before the oil on the journal reaches the wiper ribs, sufficient oil will have moved along the journal to lubri-

cate its end portion. The oil removed from the rotating journal flows into depressions 24 and back to the lubricant cellar. The features described are effective for recapturing the oil escaping to the outer ends of the bearings and for returning the recaptured oil to the lubricant cellar where it may be pumped again to the journal surface.

A journal wiper of the kind described will wear quickly to fit a journal which has been worn or machined to a diameter less than its original diameter. Ordinarily, driving journals eleven inches in diameter, when new, are kept in service until they have been reduced by wear and machining to approximately ten and one-half inches.

Wear pads 19, upon engaging the journal, reduce the rate of wear of the wiper members because of the inclusion therein of wear resisting material and because of the increased area in engagement with the journal which provides larger lubricated areas between the wiper and journals. Wear is further reduced because the shape of the pads 19 permits the accumulation of a greater amount of oil between the pads and the journal to lubricate the same. Such increased lubrication would not be possible merely by increasing the area of the wiping ribs if they were not maintained in spaced relation to effect the journal scraping action.

The details of construction may be varied substantially according to the invention, and the exclusive use of those modifications coming within the scope of the claims is contemplated.

What is claimed is:

1. In combination, a journal, a journal wiper, and means to urge said wiper into engagement with said journal, said wiper having spaced diagonal ribs adapted for initial wear to the contour of said journal, wear resisting pads positioned between but spaced from said ribs and adapted to engage said journal after said ribs have worn to the journal contour, and grooves between said ribs and said wear pads to lead surplus oil away from the outer end of said journal.

2. In combination, a journal, a journal box having a cellar and rotatably mounting said journal, means for lubricating said journal, and a journal wiper comprising an arcuate member

having spaced diagonal ribs to initially engage said journal and to wear quickly to the contour of said journal, wear resisting pads positioned between but spaced from said spaced ribs and engaging said journal after said ribs have worn to the journal contour, there being depressions between said ribs and said pads to lead surplus oil away from the outer end of said journal, and means for yieldingly maintaining said journal wiper in engagement with said journal.

3. A journal wiper comprising an arcuate member having spaced diagonal ribs adapted to initially engage a journal and to wear quickly to the journal contour, a pad of wear resisting material positioned between and spaced from said ribs and adapted to engage said journal after said ribs have worn to the journal contour, and a groove between one of said ribs and said pad to lead surplus oil away from one side of the member and discharge it to the other side of the member.

4. A journal wiper comprising an arcuate member having spaced diagonal ribs adapted initially to engage a journal and to wear quickly to the journal contour, and pads of less height than said ribs and spaced therefrom and adapted to engage said journal after the ribs have worn to the journal contour, said pads being provided with inserts of fibrous wear resisting material to engage the journal face and reduce further wear of said pads and said ribs.

5. A journal wiper of the kind described in claim 3 having a rib extending substantially transversely to and being of substantially the same height as said diagonal ribs and being positioned adjacent the sides of the wiper from which the groove leads and adapted to engage the journal to prevent flow of surplus oil towards the adjacent side of the wiper.
